UNITED STATES PATENT OFFICE

2,126,969

SEPARATOR FOR UNDERFIRED DOMESTIC
WATER HEATERSClarence H. Morrow, Shaker Heights, Ohio, as-
signor to The Hotstream Heater Company,
Cleveland, Ohio, a corporation of Ohio

Application September 24, 1934, Serial No. 745,224

3 Claims. (Cl. 126—350)

This invention relates to improvements in domestic water heaters of the underfired type, the invention having for its general object the increasing of the efficiency of such a heater by the addition thereto of what is here termed a combustion separator.

More particularly, the present invention relates to an underfired domestic water heater in which the burner thereof has associated therewith the present combustion separator, the function of which is to prevent the products of combustion produced by said burner from mixing with the secondary air below the burner. As a result, the efficiency of the burner, and hence of the heater, is greatly increased, with very little change in the construction cost of the heater.

A further feature of the present combustion separator is the condensation-confining flange thereof, the effect of which is to maintain in the products of combustion zone above the burner, for reevaporation, any condensation which may occur therein.

Other features and advantages of the present combustion separator are in part obvious and in part will appear more in detail hereinafter.

In the accompanying drawing, in which one embodiment of the present invention is illustrated, Fig. 1 is a vertical sectional view of the lower portion of a typical domestic water heater of the underfired type, said heater having associated with the burner thereof the present combustion separator; and Fig. 2 is a cross-sectional view of said heater just above the combustion separator thereof, the view being on the line 2—2 of Fig. 1.

Referring to said drawing, 1 indicates the cylindrical insulated side wall of the water tank of the heater, the concave bottom wall 2 of which is arranged above the lower end of said side wall so as to form within said side wall and below said bottom wall a chamber 3 for a burner 4, the bottom of said chamber being closed by a suitable metal base member 5 bolted or otherwise suitably secured to inwardly extending flanges 6 on the lower ends of a pair of opposed brackets 7, the intermediate portions of which are bolted or otherwise suitably secured, at 8, to the tank side wall 1. Extending upwardly from the tank bottom wall 2, in communication with the burner chamber 3 therebelow, is a suitable flue pipe 9 for carrying away the burned gases or products of combustion produced by the burner 4, and extending down into the tank and terminating adjacent the bottom wall 2 thereof is the usual cold water supply pipe 10, the hot water delivery pipe

of the heater not being shown. Preferably and as here shown, the tank is supported on suitable legs 12 and the burner chamber base member 5 is provided with a suitably sized secondary air inlet opening 13.

Although the burner 4 may be an oil burner, it is here shown as a gas burner, being suitably mounted on the inner end of a lateral feed tube 14 extending through and supported by the tank side wall 1, the enlarged outer end of said feed tube being provided with the usual shutter-controlled primary air openings (not shown) and having suitably secured thereto a gas inlet conduit 15, the flow of gas through which is controlled by a suitable valve 16.

To increase the efficiency of the burner 4, and hence of the heater, the present combustion separator is suitably associated with said burner, the function of said separator being to prevent the products of combustion produced by said burner from mixing with the secondary air below the burner. The combustion separator here shown is a simple metal member 18 of plate-like form disposed horizontally just above said burner and having a suitable opening 19 in alignment therewith and corresponding thereto in size. As a result of said separator, the chamber 3 is divided into an upper products of combustion compartment and a lower secondary air compartment, as clearly shown in Fig. 1.

Although any suitable means may be utilized to maintain said combustion separator in proper association with said burner, the present combustion separator is bolted or otherwise suitably secured to inwardly extending flanges 20 with which the brackets 7 are provided at their upper ends.

By the use of the present combustion separator, the products of combustion produced by the burner 4 within the upper compartment of chamber 3 are effectively prevented from mixing with the secondary air below said burner in the lower compartment of said chamber. As a result, improper, inefficient combustion, due to circulation of burned gases around and through the burner, is effectively eliminated. Moreover, said combustion separator aids in directing to the burner, for combustion purposes, the secondary air therefor, the amount of which secondary air is controlled by the size of the secondary air opening 13 in the base member 5. The efficiency of the burner, and hence of the heater, is therefore materially increased, with but slight change in the construction cost of the heater.

In order to confine within the products of

combustion zone above said burner, that is, within the upper compartment of chamber 3, for reevaporation, any condensation which may occur therein, the present combustion separator 5 is provided around the burner opening 19 thereof with a suitable condensation-confining flange 22.

Other features and advantages of the present combustion separator will be apparent to those skilled in the art to which the invention relates.

10 What I claim is:

1. In an underfired domestic water heater, a container for the water to be heated, wall means providing a substantially closed chamber below said container, a burner in said chamber, and a 15 transversely disposed separator in said chamber adjacent said burner and provided with an opening therefor, said separator separating said chamber into a products of combustion compartment above said burner and a secondary air compartment below said burner, said wall means being provided with a secondary air inlet, the cross-dimensional size of which is materially less than that of said chamber.

2. In an underfired domestic water heater, a 25 container for the water to be heated, wall means providing a substantially closed chamber below said container, inlet means outside of said chamber for supplying primary air to said burner, and a transversely disposed separator in said chamber adjacent said burner and provided with an 30 opening therefor, said separator separating said

chamber into a products of combustion compartment above said burner and a secondary air compartment below said burner, said wall means being provided with a secondary air inlet, the cross-dimensional size of which is materially less than that of said chamber. 5

3. In an underfired domestic water heater, a container for the water to be heated, wall means providing a substantially closed chamber below said container, a burner in said chamber, and a 10 transversely disposed separator in said chamber just above said burner and provided with an opening therefor, said separator separating said chamber into a products of combustion compartment above said burner and a secondary air 15 compartment below said burner, said wall means being provided with a secondary air inlet, the cross-dimensional size of which is materially less than that of said chamber, the opening in said separator being of substantially the same cross-dimensional size as that of said burner and said separator being provided at the edge of said opening with an upwardly and inwardly extending flange, said flange serving not only to confine in said products of combustion compartment any 20 condensate on said separator but also serving to direct inwardly and upwardly over said burner the secondary air passing through said separator opening from said secondary air compartment. 25
